RAILWAY AXLE JOURNAL DUST GUARD AND OIL RETAINER

James J. Hennessy, Chambersburg, Pa., assignor to Hennessy Lubricator Company, Inc., Chambersburg, Pa., a corporation of Delaware

Application December 15, 1954, Serial No. 475,455

13 Claims. (Cl. 286—6)

The invention relates to railway axle and journal box assemblies and more particularly to the formation of a dust guard and oil seal between the rear opening of the box and the adjacent portions of the axle.

When a railway journal and bearing are adequately lubricated, there is usually a tendency for superfluous oil to flow along the journal towards the hub of the wheel mounted on the axle and to be thrown off the journal at the outer edge of the fillet at the inner end of the bearing and also, if not arrested, at the outer edge of the fillet at the inner end of the shoulder between the journal bearing and the wheel seat. These edges may move outwardly of the box far enough to result in loss of oil from the box.

Many dust guards and oil seals have been proposed embodying various forms of pressure seals engaging the inner wall of the journal box and the surface of the adjacent portion of the axle. Some of these seals are effective when originally installed and particularly if there is no excessive play of the axle and journal box relative to each other lengthwise of the axle. The effectiveness of such seals may be lost when the material contacting the axle becomes hardened by aging or by dirt and particularly when the wear between the ends of the journal bearing and the journal collar and fillet permits the journal to play back and forth in the box an amount which brings the inner end of the intermediate portion of the axle, between the journal and the wheel seat, outside the rear wall of the dust guard pocket portion of the journal box.

The main object of the present invention is to prevent the loss of oil along the journal as indicated above.

Another object is to provide a simple, inexpensive, serviceable device which may be readily installed, and replaced, in the usual journal box dust guard pocket.

The invention comprises a device which surrounds the axle and may move therewith transversely of the axle axis and forms in effect a rearward extension of the dust guard cavity in the box to trap oil thrown off by the axle fillet edges irrespective of wiper action of the guard.

In the accompanying drawings illustrating the invention, Figure 1 is a vertical section through an American Association of Railroads (A. A. R.) journal box bearing and wedge mounted upon an axle journal with associated dust and oil guard.

Figure 2 is a horizontal section taken on the line 2—2 of Figure 1 and drawn to a larger scale.

Figure 3 is a detail section corresponding to the lower right hand portion of Figure 1, but to a larger scale, and showing the box moved along the axle a substantial distance to the left of the position shown in Figure 1.

Figure 4 is a detailed section corresponding to Figure 3 but showing the box moved along the axle to the right of the position shown in Figure 1.

Figure 5 is a front view of a portion of the guard shown in Figures 1—4.

Figure 6 is a similar view of another portion of the guard.

2

Figure 7 is a rear view of another portion of the guard.

Figure 8 corresponds to Figure 3 but shows another form of the invention.

Figure 9 corresponds to Figure 4 and shows the structure of Figure 8 with the box and guard in a different position relative to the axle.

Figure 10 is a rear view of the rear piece of the guard unit shown in Figures 8 and 9.

Figure 11 is a detail section corresponding to the lower portion of Figure 8 but showing another form of the invention.

Figure 12 is a similar section showing another form of the invention.

The journal box illustrated is the same as the usual A. A. R. standard box, including a bottom wall 1, a top wall 2, and spaced rear walls 3 and 4, apertured to receive the axle and forming a dust guard pocket P between them. The axle includes a wheel seat portion 5, a journal portion 6 of smaller diameter, and an intermediate or dust guard portion 7 having a diameter larger than the journal but smaller than the wheel seat, the peripheries of journal 6 and intermediate portion 7 terminating in fillets 8 and 9, respectively. The box is mounted upon the journal by the usual bearing 10 and wedge 11.

The oil and dust guard assembly comprises three units illustrated in Figures 5, 6, and 7, respectively. The main part of the left hand unit is a plate 15 which has a semi-circular lower contour 16 and an angular upper contour 17 and a relatively large-diameter aperture 18. The right hand face 19 of the plate is substantially smooth and flat springs 20 are secured to the left hand face.

The main part of the middle unit is formed by a plate 21 having a contour corresponding to plate 15 and having an aperture 22 of smaller diameter than aperture 18 and formed by a collar-like flange 23. Fitting within flange 23 is a cylindrical sleeve 24 projecting beyond the right hand face of plate 21 and terminating in an inturned annular flange 25, the inner periphery of which has a diameter less than aperture 22 but greater than the diameter of axle wheel seat 5. Member 24, 25 is of plastic material too stiff to distort noticeably under manual thrust but deformable under higher pressure such as will be exerted by thrust between the journal box and the axle when they shift transversely of the axis. The material possesses sufficient elasticity to resume its original form when such pressure from the box and axle is relieved. A wiper of readily flexible material has a portion 26 seated against sleeve 24 and has an inturned flange 27, which may flex to fit around the axle intermediate portion 7 (see Figures 1 and 3) or around the wheel seat portion 5 (see Figure 4). A cylindrical retainer band 28 may fit within wiper portion 26 and rivets 29 may pass through elements 23, 24, 26, and 28 to secure them together.

Preferably band 28 has upper and lower lugs 30 (Figure 6) projecting inwardly towards the axis of the device and limiting the relative movement of the assembly vertically of the axle. Wider lugs 31 project inwardly from band 28 at each side of the axle and limit horizontal movement of the axle and box relative to each other transversely of the axis. Lugs 31 do not project from band 28 as far as lugs 30 and therefore accommodate more play of the journal transversely than vertically of the arcuate face of bearing 10, but when contact is made between the axle intermediate portion 7 and either of lugs 31, the latter will resist further movement of the journal by the thrust of the opposite vertical edges of plate 21 against the side walls 12 of the journal box pocket and prevent damage due to rough handling of the car. The lugs approach the axle close enough to assure the unit always being centrally located with respect to the journal and to follow the journal in its shift-

60
65
70

ing in the box transversely of its axis and maintaining contact between the wiping ring and the journal. The arrangement provides for contact between the axle, the guard, and the sides of the box before the journal bearing 10 can be lifted upwardly and moved laterally far enough to result in excessive wear of the bearing and retaining ring.

The right hand unit of the assembly comprises a plate 35 similar in contour to plates 15 and 21 but having an aperture 38 of sufficient diameter to freely receive flange 23. A liner 36 of sponge rubber or similar sealing material is secured to the rear face of plate 35 by cement or staples.

When the assembly is assembled and inserted in the journal box pocket P, springs 20 thrust the units together and compress liner 36 against journal box rear wall 4. With this arrangement, the journal may play back and forth in the box lengthwise of the axle to the extent indicated in Figures 3 and 4, or even farther, without contact between wiper 27 and the axle being broken. The lubricant thrown off from fillet 8 in either position, and fillet 9, in Figure 4 position, will be trapped by the guard and cannot escape through the opening in the box rear wall 4. The relatively stiff seal member 24, 25 freely receives the wheel seat portion 5. Since the substantially rigid member 24, 25 does not contact the wheel seat shoulder, there will be no tendency to rupture flange 25 and wiper 27, as could occur if there were unyielding contact between either of the elements 24, 25 and fillet 9 during relative longitudinal movement of the axle and box.

A simpler two unit assembly is shown in Figures 8, 9, and 10, in which the axle and journal box are the same as previously described and the left hand unit 40 corresponds to the left hand unit previously described, except that, if necessary, its springs 41 will be somewhat deeper than springs 20. The remaining unit comprises a collar-like part 42 with an outturned flange 43 at its left hand end and an inturned flange 44 at its right hand end. The diameter of the inner periphery 45 of flange 44 is large enough to freely receive wheel seat 5 as the axle and box move relative to each other to the position shown in Figure 9. Any oil thrown off at fillet 9 will be discharged against the inner face of element 42 and returned to the journal box, rather than escaping through the opening in box rear wall 4. A liner 46 is applied to the right hand face of flange 43 and corresponds in structure and function to liner 36 previously described.

Preferably part 42 fits within the opening in box rear wall 4 and moves with the box transversely of the axle. Such movement is limited by contact between the journal and flange 45 which is thick enough and strong enough to resist firmly and stop the relative movement without collapsing.

Figure 11 shows a guard and seal similar to that shown in Figures 8, 9, and 10, but the inturned flange 50 on collar 51 is provided with a relatively thin, integral terminal 52, the inner aperture of which is smaller than the diameter of the intermediate dust guard portion 7 of the axle and therefore the terminal is deflected to form a wiper during normal operation. At the same time, it may yield further to receive the axle wheel seat portion 5 in the event of such unusual relative movement of the box and journal lengthwise of the axle.

Figure 12 shows another arrangement in which the collar portion 60 of the guard and the inturned flange 61 are tapered from the guard outer flange 62 to the inner periphery of the flange 63 and the entire flange 61, 63 may flex to accommodate movement of the axle wheel seat 5 inwardly of the journal box.

In all forms of the invention there is a closure part seated against the inner face of the rear wall of the box and having a collar extending outwardly through the opening in the box rear wall and terminating in an

inturned annular flange spaced from the inner face of the box rear wall and forming, in effect, a rearward extension of the dust guard pocket P in the box. This extension is always to the right of the axle fillet to which oil may flow and be discharged radially of the axle and this relation of the pocket extension to the oil discharging fillet is maintained during shifting of the box longitudinally of the axle. Also, the upper edge of the lower portion of the inturned annular flange of this pocket extension is at a higher level than the adjacent edge of the pocket inner end wall 3. This difference in levels insures the return to the box sump of surplus oil trapped by the pocket extension elements even though oil in the dust guard pocket may rise above the level of the upper edges of the box end walls.

The extension members 24, 25, 42, 44, 50, 51, 60 and 61 are preferably formed of a nylon plastic such as made under the trade name "Zytel" which has durable elastic characteristics adapting it for the purposes described.

The arrangement shown in Figures 1-7 is particularly effective when applied to cars used in dumping machines at coal and ore docks or the like where the entire car is rotated about a longitudinal axis 180° or more to discharge its contents.

The details of the structure may be varied other than as shown without departing from the spirit of the invention and the exclusive use of those modifications coming within the scope of the claims is contemplated.

What is claimed is:

1. In combination with a railway axle and journal box in which the axle includes a wheel seat portion, a journal portion, and an intermediate portion of larger diameter than the journal portion and of smaller diameter than the wheel seat portion, there being fillets between said journal portions, and the journal box has inner and outer upright walls forming a dust guard pocket between them and having openings normally surrounding the axle intermediate portion, an oil retaining device comprising a plate-like member movable into the dust guard pocket transversely of the axis of said openings and having a similar opening and provided with a collar-like member surrounding said opening and projecting from the plate-like member into the opening in the outer upright wall a distance corresponding to the thickness of said end wall and terminating at its outer end in a radially inwardly extending flange, the internal diameter of which exceeds the diameter of said axle wheel seat portion whereby the flange is adapted to freely receive said axle portion, as the box shifts inwardly from the end of the axle, and thereby form a lubricant trap surrounding the fillet between said wheel seat portion of the axle and said intermediate portion of the axle.

2. A railway axle, journal box and oil retaining structure according to claim 1 which includes a layer of compressible sealing material positioned between the plate-like member and the pocket outer wall.

3. A structure according to claim 1 which includes a readily deformable wiper extending radially inwardly from the collar-like member and surrounding and slidably contacting the axle.

4. A railway axle, journal box and oil retaining structure according to claim 1 in which the plate member and the collar extension with inturned flange constitute a single integral unit with the inturned flange opposing the axle transversely of its axis and formed of material adapted to resist shifting of the axle and the oil retaining device transversely of the box under normal pressure from thrust between the journal box and axle transversely of the axle but deformable under abnormal pressure and possessing elasticity sufficient to cause the unit to resume its original shape after being relieved from such abnormal deforming pressure.

5. A railway axle, journal box and oil retaining device according to claim 1, in which there are elements

on the plate-like member at the top and bottom of the opening therein projecting towards the axis of said opening and holding the axle and plate against substantial relative movement vertically of the box.

6. A railway axle, journal box and oil retaining device according to claim 1 in which the collar projecting from the plate-like member fits snugly within the axle-receiving opening in the journal box outer wall, whereby the plate-like member and the elements carried thereby move with the box transversely of the axle.

7. An oil guard for a railway axle having a journal portion and a wheel seat portion of larger diameter than the journal portion, comprising a cylindrical body, an annular flange extending radially outwardly from one end of said body and an annular flange extending radially inwardly from the other end of said body, said flanges being of form-sustaining material and section, the diameter of the inner periphery of the latter-mentioned flange being greater than the diameter of the wheel seat portion of the axle for which the oil guard is constructed, there being an annular liner of compressible material surrounding the cylindrical body and lying against the radially outwardly extending annular flange and spaced a substantial distance lengthwise of the cylindrical body from the radially inwardly extending flange.

8. A railway axle journal box dust guard and oil retainer according to claim 7 in which a wiper of readily flexible material projects inwardly from the inner periphery of the inwardly extending flange.

9. An oil guard according to claim 7 in which the cylindrical body and flanges consist of an integral unit of plastic material which is too stiff to distort under manual thrust, with the radially inwardly extending flange, at least, being deformable under pressure exerted between a journal box and axle but possessing elasticity sufficient to cause the flange to resume its original shape after such deforming pressure is removed.

10. An oil guard according to claim 7 which includes restrictive elements at the top and bottom of the cylindrical body projecting radially inwardly toward the axis of the body and in alignment with the radially outwardly extending flange so that the effective inside vertical diameter of the body at these elements is less than its horizontal diameter.

11. An oil guard for a railway axle having a journal portion and a wheel seat portion of larger diameter than the journal portion, comprising a cylindrical body, an annular flange extending radially outwardly from one end of said body and an annular flange extending radially inwardly from the other end of said body, said outer flange being of form-sustaining material throughout its section and the inner flange being of form-sustaining section except for its inner margin, the inner diameter of the outwardly extending annular flange and of said body and of the form-sustaining section of the inwardly extending flange being greater than the diameter of the wheel seat portion of the axle for which the oil guard is constructed, there being a relatively thin flexible integral margin on the inwardly extending flange having a diameter less than the diameter of the wheel seat of the axle for which the oil guard is constructed.

12. An oil guard according to claim 11 in which the cylindrical body and inwardly extending annular flange and its terminal are tapered gradually from the outwardly extending flange to the terminal.

13. An oil guard according to claim 7 which includes a detachable yielding member alongside the annular radially outwardly extending flange for exerting thrust on the latter axially of the cylindrical body when the yielding member is seated against a dust guard pocket wall, the axial length of the cylindrical body over its radially outwardly extending flange and the radially inwardly extending flange being less than the distance between the outer faces of the annular liner and said yielding member when the cylindrical body and member are assembled in functioning relation.
